UNITED STATES PATENT OFFICE.

JOHN F. GOLDING AND GEORGE B. DURKEE, OF CHICAGO, ILLINOIS,
ASSIGNORS TO THE EXPANDED METAL COMPANY.

MACHINE FOR MAKING SLASHED METALLIC SCREENING.

SPECIFICATION forming part of Letters Patent No. 320,241, dated June 16, 1885.

Application filed August 28, 1884. (No model.)

To all whom it may concern:

Be it known that we, JOHN F. GOLDING and GEORGE B. DURKEE, citizens of the United States, residing in Chicago, in the State of Illinois, have invented certain new and useful Improvements in Machines for Simultaneously Cutting and Expanding Slashed Metallic Screening, of which the following is the specification.

Figure 1 is a front view or elevation. Fig. 2 is a plan view. Fig. 3 is an end view opposite to end where power is applied. Fig. 4 is a vertical sectional view through line 4 4, Fig. 1. Fig. 5 is detail of cutters in position to receive the metal for cutting and expanding. Fig. 6 is detail of knives in position after having cut and expanded the metal. Fig. 7 is a top view of lower bar, showing position of lower series of cutters and the guides which cause the bar holding the lower cutters to move slightly obliquely to itself, but parallel with each lower cutter. Fig. 8 is a side view of one end of lower bar, showing cam for giving said bar longitudinal movement, and plunger which holds the dog that actuates the cam. Fig. 9 is an end view of end of lower bar shown in Fig. 8. Fig. 10 is a detail of cam movement to return lower bar to first position, as hereinafter will be explained. Fig. 11 is detail of ratchet and spring-catch for feeding sheet metal to cutters. Fig. 12 is a view of metal partially cut and formed and partially uncut.

The nature and object of this invention is to provide a machine for cutting and expanding slashed metallic screening, which was the subject of Patent No. 297,382, issued to John F. Golding, one of the applicants hereof.

A and B are the posts of the frame of the machine.

C is the front cross-beam, supported by the posts A and B.

D is the main shaft of machine, located at top and working in suitable bearings in the posts A and B. On this shaft are the eccentrics E E and eccentric F, the last being located near the center of shaft D.

G is the driving-shaft, suitably boxed in both end posts A B, and carrying drive-wheel H and spur-wheel I.

To the shaft E is attached a large cog-wheel, J, driven by spur-wheel I.

K is the upper bar, holding the upper series of cutters and actuated in a vertical plane by eccentrics E E and links L L. 55

M is a brace extending from one post to the other to strengthen the machine.

N is the lower bar, holding the lower cutters. This bar is provided with inclined offsets y y, and is movable between guides y' y', one of which is on front side of bar C, and the other is on back of bar Z. Bar Z is a cap extending along face of bar C, and provided with guides corresponding with the guides on front of bar N. The object of these guides is to give the bar N a slight oblique movement to cause the cutters attached to it to move parallel to the cutters on upper bar, K.

O is an eccentric on end of shaft D, and by pitman P connected to plunger Q, which works 70 through guides R R.

On plunger Q, Fig. 10, is fastened the box S, in which works the dog T. This dog works against the cam U, which is attached to the lower bar, N, on its side near its end. This 75 cam is cut beveled on the under side at V, and on the upper side it is formed with a scalloped bevel at W.

X is a spring fastened at its lower end to the plunger Q, the upper end resting against the 80 outer end of dog T. This spring presses the dog against the cam U.

To the lower bar, N, is attached a series of cutters, d, by means of screws b, Figs. 5 and 6, where they are shown in detail. In each 85 cutter is the slot e, through which the screw b works to admit of their being adjusted when worn. The form of these cutters is shown in the first one d of the series. The front edge is cut beveling, as shown at a. These cutters 90 are placed one overlapping the other, as shown at d d, Fig. 7, and also in Figs. 1 and 2.

To the upper bar, K, Fig. 1, are fastened a series of cutters, g g, attached to this bar in a similar manner, each one overlapping the 95 other in the same manner, and the rear lower part of each upper knife is cut beveling, as shown at f f, Figs. 1 and 5.

h h h, Fig. 2, is a frame attached to the posts A B, and extending backward in brace form, 100 which is more clearly shown in Figs. 3 and 4.

i i, Figs. 2, 3, and 4, are two ratchet-bars, supported at their rear ends by the frame h, and secured to a bar, b', at their front ends.

The bar b' reaches from post A to B over the bed c' of the machine, just back of the cutters, and is supported at its center by braces $d' d'$, reaching from posts A B.

5 j , Fig. 2, is cross-bar extending from ratchet-bar i to i , and sliding beneath them. At each end of cross-bar j is a spring, t' , Fig. 11, one end being fastened to the cross-bar j and the other working against ratchet i , so placed that 10 it allows the cross-bar j to freely move forward toward the cutters, but prevents it moving backward. By turning the cam t' , located above the spring t' , the free end of this spring is depressed, which allows the cross-bar j to be moved backward.

15 k , Figs. 2 and 4, is an angle-bar extending lengthwise of shaft G, and attached thereto by two or more collars extending around said shaft G freely working thereon, and connected 20 to the main shaft D by the pitman l , working on eccentric F.

25 To collar k , Figs. 2 and 4, is attached dog m , and extending downward, the lower end working between heads $a' a'$. These heads are fastened to the ratchet-bars $i i$, and there are two of these dogs m .

30 d'' is a brace extending from posts A B to center and top of front of cross-bar C, to steady and support the machine.

35 The operation of our machine is as follows: Motion is communicated to the main driving-wheel H by belt or otherwise. As the eccentrics on E E revolve, the bar K is raised and lowered, which works the cutters $g g$ fastened thereto up and down in vertical planes and over the cutters $d d$ in lower bar, N. The position of the cutters before making their cutting movement is shown in Fig. 5—that is, they are separated, leaving a space between 40 them. As the upper cutters descend in a vertical plane, the bevel edge of the upper cutters move along the surface of the bevel edge of the lower cutters, and the lower bar, N, to which the lower cutters are attached, being 45 allowed to freely move longitudinally in its bearings, the descent of the upper cutters causes the lower cutters to move horizontally, and when the upper cutters have finished their downward movement the two sets of cutters 50 are in the positions shown in Fig. 6. The downward and upward movement of upper cutters is caused by the eccentrics on shaft D. The return movement of lower shaft, N, with its cutters is accomplished as follows: As the 55 downward movement of the cutters is made the plunger Q also descends, and at the same time the dog T, Fig. 10, takes its position on the lower bevel of cam U, and as the plunger rises the bar N is returned to its original position.

60 A sheet of metal of the proper size is placed in position on bed C', with the rear edge resting against bar j , as shown at s, Fig. 4. The eccentric F on shaft D causes the collar k to rock, which in turn causes the lower 65 end of dog m to vibrate. This causes the ratchets $i i$ to move backward and forward, which in turn causes the cross-bar j to move forward

and feed the metal to the cutters, and as the metal passes between the two sets of knives it comes out in strands cut and bent, (leaving 70 uncut intervals,) which form and maintain a mesh, as more plainly shown in Fig. 12. In Fig. 1 it is shown in the act of issuing from between the knives.

75 It will be observed that there are intervals where the material is uncut, and that these uncut intervals form the union of the meshes. This uncut interval is formed as follows: The lower bar, N, is moved a certain distance. This distance is such that the upper corner of 80 the beveled edge of the lower cutters is a little beyond the lower corner of the beveled-edged corner on upper cutters, and this distance between these two corners determines the uncut interval in the metal. The feeding 85 movement is so adjusted that the metal is fed at each movement just far enough to form the strand, and as the upper cutters descend they push ahead of them that part of the metal, and at the same instant cut it from the main part 90 of the metal, and this cut strand lies between the beveled edges of the two cutters and against the lower edges of the upper cutters. The entire piece of metal is consumed, and no part or portion is lost or wasted.

95 It will be observed that the metal is fed at an angle with the line of the cutters and parallel with the face of each cutter, and that the bar j , which forces the metal between the cutters, is set at an angle with the line of the cutters and parallel with the face of each cutter.

100 The reason why we feed the metal at an angle with the main cutting-bars of the machine is, first, that the said bars may be in line with the main shaft, and, second, that the metal may encounter the cutters first on one corner and in a line parallel with the surface of each cutter. The object in beginning to cut at one corner of the metal is that each cut, strand, or loop will be set free by a cut immediately back of it, said cut or cuts always supplying as much length of strand as the preceding knives consume, as the pressing the strands downward and forming the mesh causes the cut and spread part of the metal to assume 110 a form shorter than the uncut part.

115 The improvement in the art of making screening from metallic plates or sheets incidental to the operation of this machine is claimed in our application for a United States Patent filed 120 August 28, 1884, Serial No. 142,328.

We claim—

125 1. In a machine for cutting slashed metallic screening, the combination of the upper bar, K, provided with the cutters $g g$ and having a vertical movement, with the lower bar, N, provided with cutters $a a$ and having a longitudinal movement, as and for the purpose shown.

130 2. In a machine for cutting slashed metallic screening, the bar K, provided with cutters cutting over bar N, provided with similar knives, the first working vertically while the second is working horizontally, to provide the

necessary cutting-surface and space for the cut loops to expand.

3. In a machine for cutting slashed metallic screening, the cutters in each cutter-bar arranged one overlapping the other for the purpose of simultaneously cutting a number of slashes and forming loops, leaving uncut sections between them for the purpose of forming a continuous mesh from one piece of metal without cutting away or wasting any of the material, as and for the purpose shown.

4. The combination of the cutter-bar pro-

vided with cutters set at a slight angle with the surface of the bar with guides whose faces are parallel with the faces of the cutters, causing the cutters to travel in a line with their own faces and the bar to have a slight oblique movement, substantially as shown. 15
